COMBINED STOPPER AND WATERING SPOUT

Lucille Lillian Worden, Williston, N. Dak.

Application August 29, 1955, Serial No. 37,703

Term of patent 14 years

(Cl. D58—10)

Figure 1 is a plan view of a combined stopper and watering spout, according to the present invention, showing my new design;

I claim:

The ornamental design for a combined stopper and watering spout, as shown.
